ATTORNEYS

UNITED STATES PATENT OFFICE.

GIORGIO ADELMO, OF SPRING VALLEY, ILLINOIS.

HOLDING DEVICE FOR VIBRATORS.

Application filed October 17, 1924. Serial No. 744,298.

To all whom it may concern:

Be it known that I, GIORGIO ADELMO, a citizen of Italy, and a resident of Spring Valley, Bureau County, State of Illinois, have invented a new and useful Improvement in Holding Devices for Vibrators, of which the following is a full, clear, and exact description.

My invention relates to improvements in holding devices for vibrators of the hand type, and consists in the combinations, constructions, and arrangements herein described and claimed.

This application is a continuation in part of my co-pending application for patent on razor operating device, Serial No. 699,914, filed March 17, 1924.

An object of my invention is to provide a holding device for vibrators in which a razor with a straight edge may be clamped in either right or left hand position as in shaving the opposite sides of the face.

A further object of my invention is to provide a holding device for vibrators in which various devices such as combs, tooth brushes, and various types of vibrator appliances may be supported in operative position on the vibrator, and interchanged at will.

A further object of my invention is to provide a holding device for vibrators in which the holding device may be inverted to alter the angle at which the instrument or device secured therein is disposed relative to the oscillatory plane of the vibrator armature.

A further object of my invention is to provide a device of the type described that is compact in form, which is light in weight, which is durable, and thoroughly practical for the purpose intended.

Other objects and advantages will appear in the following specification, and the novel features of the invention will be particularly pointed out in the appended claims.

My invention is illustrated in the accompanying drawings forming part of this application, in which—

Figure 1 is a front elevation of an embodiment of my invention,

Figure 2 is a partial side elevation of the mechanism illustrated in Figure 1,

Figure 3 is a top plan view of the mechanism illustrated in Figure 1.

In carrying out my invention, I make use of a vibrator mechanism consisting of a casting comprising two cooperating parts A and B. These parts may be constructed of molded composition such as bakelite or other well known composition having insulating properties. The vibrator mechanism having an angular portion 31, which extends exteriorly of the casing, is disposed therein, and conducting wires 16 are projected through the casing by means of which the electric vibrating mechanism contained therein may be properly connected with a current source. The casing is provided with vents 2 for assisting in cooling the vibrator mechanism within the casing.

The parts A and B of the casing are held together by screws 5, projected therethrough.

The movement of the armature is in an oscillatory path, parallel with the conducting edges of the casing members A and B.

My improved razor holding device is arranged for disposition upon the angular portion 31 and consists in a body member 30 having an angular loop-shaped member 21 at one end thereof which is arranged to fit over the angular part 31 of the armature. A thumb screw 32 projected through the body member 30 adjacent to the loop portion 21, provides means by which the loop 21 may be slightly contracted, and in this manner, securely clamp the body member 30 upon the armature.

The body member 30 is provided with a depending member arranged to yieldingly engage with the handle 33 of the ordinary type of razor 34. This depending member consists in a pair of spring clamps 35 carried by the body member 30 and disposed at a slight angle with respect to the axis of the part 31 of the armature.

A separator 36 is disposed between the spring clamping portions 35 and is arranged to extend slightly below the lowermost ends of the members. The lowermost ends of the members 35 are dished outwardly as shown

at 37 so that the split handle 33 may easily be moved beyond the lowermost ends of the spring clamping members 35 when placed astride a separator 36 in the manner shown in Figure 2.

5 The clamping members 35 function to yieldingly hold the handle 33 of the razor against both longitudinal and lateral movement relative to the body member 30 of the 10 clamping mechanism.

Means for supporting the blade 38 of the razor 34 in the holding device is provided as follows:

15 A strap 40 is hingedly mounted at 41 to the body member 30 in such a manner as to permit the strap 40 to be moved to the position shown in full lines in Figure 1 or to the position shown in dotted lines, at will. In both cases the strap 40 lies in a plane 20 substantially parallel with the separator 36.

25 The strap 40 has disposed at its outermost end a spring pressed clamp 42, the work engaging part 43 of which is in turn pivotally connected to the clamping member 42 so as to completely conform with the irregular 30 configuration of the neck 50 and the razor 34. It is therefore evident that the razor blade 38 may be firmly secured against movement upon the body member of the holding device so that the vibratory motion 35 imparted to the body member 30 by the armature when current is supplied to the vibration mechanism will be evident by an almost imperceptible movement of the blade handle.

40 From the foregoing description of the various parts of the device, the operation thereof may be readily understood. The person using the device will first manually place the razor between the strap 40 and the spring pressed clamping member 42, so that the blade 39 is securely fixed against movement relative to the strap and therefore to the body member 30.

45 The strap 40 is then hinged in the position shown in full lines in Figure 1 or to the position shown in dotted lines, depending upon which side of the face is to be shaved first. The blade 30 is hinged upwardly so that the split portion thereof 50 may lie astride the separator 36 and be received between the spring pressed clamping members 35 which will securely hold the handle against both longitudinal and lateral movement.

55 The vibrating mechanism within the casting 1 is then operated so that the armature portion 31 vibrates with an exceedingly high and practically imperceptible oscillatory 60 movement. This causes a like movement of the holding device and the blades held therein. The blade is then moved over the face in precisely the same manner as if the razor were not supported, and sustained in the 65 movement by the vibratory mechanism. It

is not necessary to move the razor with a swift stroke as in the ordinary manner of shaving, but instead, the blade is moved slowly over the face and the movement of the razor which actually severs the beard is 70 that movement which is imparted to the blade from the vibratory mechanism within the casing 1.

75 In changing from side to side, it is necessary to move the handle 33 from the spring clamping members 35 and swing the strap 40 to the opposite position. When this is done, the blade 33 is moved into engagement with the member 35 and the razor is ready for use.

80 I claim:

1. A device of the type described comprising a casing, an electric vibrating mechanism mounted within said casing, and a clamping mechanism operatively connected with said vibrating mechanism for supporting the ordinary type of razor thereupon in an operative position, whereby the razor may vibrate with said clamping mechanism, said clamping mechanism comprising a 85 guide strap having a spring clamp for pressing the blade of said razor into engagement with said guide strap, and a second clamping member arranged to hold the handle of said razor against movement, said second named clamping member comprising spring portions arranged to yieldably engage with the exterior walls of said handle and a separator arranged to extend through the solid portion of said handle, said spring 90 members and said separator being in substantial registration with one another.

95 2. In a device of the type described, a clamping mechanism for supporting a razor of the ordinary type in an operative position comprising a guide strap having a 100 spring clamp thereupon for pressing the blade of said razor into engagement with said guide strap, and a second clamp member arranged to secure the handle of said razor against movement, said second named clamp member consisting of a pair of spring 105 portions arranged to engage with the exterior walls of said handle, and a separator arranged to be projected through the solid portion of said handle at a point substantially in registration with said spring portions of said second clamp member.

110 3. In a device of the type described, a clamping mechanism for supporting a razor of the ordinary type in an operative position comprising a body member, a guide strap hingedly mounted on said body member and arranged to be moved through an arc of 180° on its hinged support, said guide 115 strap having a spring clamp for pressing the blade of said razor into engagement with said guide strap, and a second clamping member carried by said body member arranged to hold the handle of said razor 120

against movement, said second named clamping member comprising a pair of spring members arranged to engage with the exterior walls of said handle, and a separator arranged to be projected through the solid portions of said handle and in substantial registration with said spring members.

4. A device of the type described comprising a casing of insulating material, an electric vibratory mechanism having an ar-

mature disposed in said casing, said armature being arranged to extend partially exteriorly of said casing, and a clamping mechanism arranged to be secured to said armature outside of said casing for supporting the ordinary type of razor, said clamping mechanism including a spring clamp for receiving the blade of said razor and a second clamp for securing the handle of said razor against movement.

GIORGIO ADELMO.
